Primary Examiner — Robert M Spear*Assistant Examiner* — Ryan Harvey(74) *Attorney, Agent, or Firm* — Woodard, Emhardt, Moriarty, McNett & Henry LLP(57) **CLAIM**

The ornamental design for an abdominal muscle exercise apparatus, as shown and described.

DESCRIPTION

FIG. 1 is a perspective view of an abdominal muscle exercise apparatus.

FIG. 2 is a left view of the abdominal muscle exercise apparatus.

FIG. 3 is top view of the abdominal muscle exercise apparatus.

FIG. 4 is a front view of the abdominal muscle exercise apparatus.

FIG. 5 is right view of the abdominal muscle exercise apparatus.

FIG. 6 is a bottom view of the abdominal muscle exercise apparatus.

FIG. 7 is a rear view of the abdominal muscle exercise apparatus; and,

FIG. 8 shows a perspective view of the embodiment of FIG. 1 with the handle in a rotated position.
